UNITED STATES PATENT OFFICE.

DANIEL GARDNER, OF NEWBURGH, NEW YORK.

PAPER TAKE-UP FOR TYPEWRITING-MACHINES.

1,364,103.

Specification of Letters Patent.

Patented Jan. 4, 1921.

Application filed January 5, 1920. Serial No. 349,404.

To all whom it may concern:

Be it known that I, DANIEL GARDNER, a citizen of the United States, residing at Newburgh, in the county of Orange and State 5 of New York, have invented certain new and useful Improvements in Paper Take-Ups for Typewriting Machines; and I do hereby declare the following to be a full, clear, and exact description of the invention, such as will enable others skilled in the art to which it appertains to make and use the same.

My invention consists in the novel features hereinafter described, reference being 15 had to the accompanying drawing which illustrates one embodiment of the same, selected by me for purposes of illustration, and the same invention is fully disclosed in the following description and claims.

20 In the use of typewriting machines, especially with manifolding work in which a number of sheets of paper and one or more sheets of carbon are placed in the paper carriage, and are fed up step by step by the line feeding mechanism, it frequently happens that an unequal feed of the sheets of the different layers, or a twisting of the multi-sheets with respect to the axis of the feed roll, or other shifting of the paper and 25 carbon sheets with respect to each other, results, causing inequalities in the writing on the different sheets and differences of alinement, which are extremely objectionable, and also necessitating in some cases the 30 removal of the sheets from the carriage and the replacing of them in the carriage, which can seldom, if ever, be effected without arranging the paper sheets with respect to each other, and affecting the alinement of 35 the work. The object of my invention is to 40 provide in connection with the paper carriage of a typewriting machine, a simple device which can be permanently or detachably secured thereto, and which comprises 45 among its members, a light frame extending above the paper roll, a paper clamp for engaging the upper edges of the sheets, a flexible connection connected to the paper clamp at one end and having its other end connect- 50 ed to a continuously acting take-up, preferably in the form of a spring drum carried by the frame. With this apparatus the operator, after inserting a series of sheets in the feed mechanism on the paper carriage, 55 can draw forward the paper clamp, and clamp it upon the upper edges of the com-

bined sheets, and preferably centrally thereof, when the tensioning device will immediately act through the flexible connection to exert an upward pull on the combined sheets 60 at all times during the writing. As the paper is spaced vertically by the line feeding mechanism, the take-up mechanism continues to exert an upward draft on the combined sheets equally during, before, and 65 after, the line spacing feed of the paper, thus assisting the paper feeding mechanism to feed the combined sheets in a perfectly straight vertical manner and preventing any movement of the sheets with respect to each 70 other, or any tendency of the sheets to feed faster at one edge than at the other, or to otherwise shift their relation with respect to the feed roll.

Referring to the drawings,

75 Figure 1 represents a perspective view of one embodiment of my improved paper tensioning device, the adjacent portions of a typewriting machine being indicated in dotted lines and the position of the paper clamp 80 and flexible connection in conjunction with the paper sheets being indicated in dotted lines also.

Fig. 2 is a side elevation of my improved device.

85 Fig. 3 is an enlarged section of the same through the spring actuated tension device, parts being shown in elevation.

In the embodiment of my invention herein shown, 1 represents a narrow frame bar provided at one end with means for securing it to the paper carriage of a typewriting machine. In the present instance, I have shown the lower end of the frame bar 1 provided with clamping jaws 2-2 for clamping the 90 upper edge of the paper guiding plate A at the rear of the paper feed roll B of the typewriting machine, the jaws being held in engagement with said plate (or other portion of the paper carriage) in any desired way, 95 as by the clamping screw 3 and wing nut 4 herein shown. 5 represents a paper clip which comprises merely a pair of gripping jaws normally held in gripping position by a suitable spring 6 in a well known way, one 100 of the jaws being provided with a thumb piece 7 to facilitate opening the jaws. 8 represents a flexible connection, one end of which is connected to the clamp 5 and passes over a roll or pulley 9 at the upper end of 105 the frame 1, and thence downward to the tensioning device, which in this instance 110

consists of a spring actuated drum 10 mounted in arms 11, secured to the rear face of the frame 1, said drum being provided internally with a spring 12, which acts at all 5 times to rotate the drum in the direction indicated by the arrow in Fig. 1. I prefer to connect one end of the spring 12 to the drum and the other end to a shaft 13 provided with a ratchet 14 engaged by a pawl 10 15 carried on one of the arms 11, and to provide the shaft 13 with a polygonal portion 16 so that it can be turned by means of a key or other suitable tool to adjust the tension of the spring, in a well known way.

15 When the apparatus is at rest the paper clip 5 will be held at the upper end of the bar or frame 1, out of the way, and the apparatus will not interfere in any way with the operation of the typewriting machine.

20 When it is desired to do manifolding, a plurality of paper sheets and carbons is inserted around the feed roll B and the operator will reach forward, grasp the paper clamp by the base and thumb piece,

25 so as to open the clamp, and drawing on the flexible connection 8, will apply the clamp to the top edges of the combined paper sheets, thus holding them firmly in proper relation with each other, and causing 30 an upward tension to be exerted upon the paper sheets by the spring drum through the flexible connection 8. As will be apparent, the spring drum will exert a constant upward pull on the paper sheets so 35 long as they remain in the machine, and as the paper carriage is operated for line spacing, the tension device will take up this space and assist in effecting a perfectly vertical feed of the paper as well as a perfectly uniform feed of all the sheets or 40 layers of paper and carbons, thus preventing any tendency of the paper to twist with respect to the roll, as well as any tendency of the paper and carbon sheets to 45 shift in any manner with respect to each other. This simple and compact device will be found to be very advantageous in securing proper feeding of the paper in type-

writing machines, especially in manifold work, although it may obviously be used in 50 connection with single sheets and will be found extremely advantageous in many cases in connection with single sheet work, especially in handling heavy backing sheets, manuscript covers, and the like.

55 When the paper has been fed as far as the feed mechanism of the typewriting machine will feed it, it will be held suspended by the paper clamp 5 until the operator releases it, by depressing the thumb piece 7, thus 60 retaining the sheets in proper relation with each other even after they have left the control of the paper feeding mechanism of the typewriter.

65 What I claim and desire to secure by Letters Patent is:—

1. A paper take-up attachment for typewriting machines comprising among its members a paper clamp for engaging the topmost edge or edges of a paper sheet or 70 sheets, a continuously acting tension device, and a flexible connection from the tension device to said paper clamp.

2. A paper take-up attachment for typewriting machines comprising among its 75 members a frame bar provided at one end with means for attaching it to the paper carriage of a typewriting machine, a continuously acting tension device, a paper clamp, and a flexible connection from the 80 tensioning device to said paper clamp.

3. A paper take-up attachment for typewriting machines comprising among its members a frame bar provided at one end with a clamp for attaching it to the paper 85 carriage of a typewriting machine, and having a pulley at the other end, a continuously acting spring actuated drum carried by said frame bar, a paper clamp for engaging the upper edge or edges of a paper sheet or 90 sheets, and a flexible connection having one end secured to the paper clamp and the other end secured to said drum and passing over said pulley.

95 In testimony whereof I affix my signature.

DANIEL GARDNER.
